SMOKING PIPE

Harold T. Blum, Glenmont, Ohio, assignor to
Briar Hill Corporation, Millersburg, Ohio, a corporation of Ohio

Application May 27, 1939, Serial No. 276,099

5 Claims. (Cl. 131—181)

The present invention is an improvement in smoking pipe structures having incorporated therein members for providing a cool, dry and controlled smoke to the user thereof and is a continuation in part of my copending applications Serial No. 250,220, filed January 10, 1939, and Serial No. 258,060, filed February 23, 1939. It is an object of the present invention to provide an improved form of pipe structure of a fire controlled type which is capable of producing a relatively cool and dry smoke.

Another object of the invention is to provide a pipe structure which will provide a cool and dry smoke and in which the weight thereof is retained to the minimum.

A further and equally important object of the present invention is to provide a commercially feasible pipe structure which is capable of producing a cooled and dried smoke and which can be readily and easily disassembled for convenient cleansing thereof.

A still further object of the present invention is to provide an improved means for controlling the firing of the tobacco within a smoking pipe structure.

Further objects of the present invention are set forth in the following detailed description of the accompanying drawing, while still further objects of the invention will be obvious from a consideration of the present device.

In the accompanying drawing:

Fig. 1 is a side cross sectional view of the smoking pipe structure comprising the present invention and having a portion of the stem thereof broken off.

Fig. 2 is an enlarged detail constructional view of a portion of the tobacco elevating members and their mounting within the pipe bowl.

Fig. 3 is a side cross sectional view of a tubular member which forms a part of the present pipe structure.

Fig. 4 is an enlarged top view of the tobacco supporting plate.

Fig. 5 is a top cross sectional detail view taken on line 5—5 of Fig. 1, and

Fig. 6 is a detail view of a resilient ring member which forms a part of the present construction.

Referring now more particularly to the accompanying drawing wherein like reference characters designate like parts, numeral 1 refers to a tubular member formed preferably of a lightweight metal such as magnesium and which is cast in one piece to form a stem portion 2 and a simulated pipe bowl 3. Threads

4 and 5 are respectively formed at the open end of the bowl portion 3 and the open end of the stem portion 2. The base of bowl portion 3 also has an inwardly extending annular flange 6 with the portion of member 1 within flange 6 removed to form an opening.

Within and mounted upon the base portion of bowl 3 is a tube 15 also preferably formed of a lightweight metal and whose interior and exterior faces are formed of a plurality of angularly related straight walls 17. The bore of said tube 15 is sized to slide over the periphery of flange 6. The upper end of tube 15 has an annular flange 31 extending substantially at right angles therefrom and a plurality of openings 16 are each formed through one of the walls 17 from the upper end of the tube downwardly to a point upon the exterior face thereof directly below flange 31.

A ring 10 formed of a heat insulating material such as wood or meerschaum, for example, is positioned with the bore 11 thereof extending contiguous from the walls 17 of tube 15. The periphery of ring 10 is stepped and has a ring 12 fixedly mounted upon said stepped portion and which ring 12 is preferably of a metallic construction but may, however, be of a heat-insulating material. Ring 12 has threads formed upon the periphery thereof for engagement with threads 4 of bowl member 3 and also an annular flange 13 extending from the upper end thereof to act substantially as a washer between the ring 10 and the upper edge of bowl member 3. The lower portion of the inner face of ring 12 tapers downwardly and outwardly towards the outer face thereof, while the circumference of the non-tapering portion of said inner face is substantially equal to the circumference of flange 31 of tube 15.

The lower face 32 of ring 10 tapers inwardly and downwardly towards the center thereof for the purpose hereinafter described.

Stem portion 2 has threads 5 in engagement with threads 8 of stem mouthpiece 9. Said stem 9 has an axial bore 34 whose cross sectional area at the smallest point thereof is substantially equal to the sum of the cross sectional areas of the openings 16 of tube 15.

Mounted within tube 15 and extending thereacross is a plate 18 whose periphery is formed of a plurality of straight walls 19 which give said periphery a decagon configuration, which is substantially equal in size and similar to the decagon formed by the walls 17 of tube 15. A

rectangular opening is formed in the central portion of said plate 18.

The rectangular head 29 of a screw section 20 is mounted within the rectangular opening of plate 18 and flattened to rivet the two members to one another. Said screw section 20 is the center member of a series of telescopic sections 21, 22 and 23. Said tubular sections 21, 22 and 23 have lefthand threads formed upon their 10 periphery as has said screw section 20. The upper portion of the inner face of each of said sections 21, 22 and 23 has lefthand threads 35 formed thereon with the remaining portions 36 of said inner faces being formed smooth. The threads 15 of screw section 20 are in engagement with the threads 35 of section 21 while, similarly, the peripheral threads of sections 21 and 22 are respectively in engagement with the inner threads 20 of sections 22 and 23. Section 22 has an annular groove 39 formed at the lower end of its interior 25 face and an outwardly expanding resilient metal ring 33 is positioned within said annular groove 39. The lower end portion of section 21 is formed solid as at 41 with an annular flange 40 formed 30 extending at right angles from the upper end thereof a distance sufficient for flange 40 to at times contact the upper face of ring 33. The lower end of screw section 20 and section 22 have annular flanges 26 extending substantially 35 at right angles therefrom, which flanges 26 contact the smooth inner faces 26 of sections 21 and 23 respectively while flange 40 of section 21 will contact the wall of the bore of section 22. Section 23 has an annular flange 24 formed extending 40 from its upper end and which is seated upon the upper edge of flange 6. The periphery of said section 23 has righthand threads 27 formed at its lower portion, which threads 27 are engaged by threads formed upon the inner wall 45 of a cap 30, which cap has a cavity formed therein whereby the lower portions of screw section 20 and sections 21, 22 and 23 may be received therein with the lower faces thereof at times contacting the inner face 37 of said cap 30 for preventing the further downward movement of 50 members 20, 21, 22 and 23. The upper edge 38 of cap 30 slidably contacts the outer face of the base portion of bowl 3 while the smooth portion 39 of section 23, as well as the lower face of flange 24, also slidably contacts flange 6.

In the assembling of the present structure, tube 15 is inserted within the bowl 3 and over flange 6. Ring 10, with its connecting ring 12, is mounted upon the open end of bowl 3 by screwing ring 12 within threads 4. The tapered edge 14 of ring 12 will contact the periphery of flange 31 of tube 15 and cause the same to be inserted within the ring 12 for positioning the walls 17 in line with the opening within flange 6 and also bore 11 of ring 10. The gradual but forceful 60 downward movement of ring 12 as the same is being screwed into position will cause the tapered face 32 of ring 10 to gradually contact the upper face of flange 31 and with a wedge-like action, 65 forcibly position the lower end of tube 15 about flange 6 and, at the same time, completely seal the interior of tube 15 from the interior of bowl 3 except for the openings 16.

Screw section 20 is screwed within the inner 70 threads 35 of section 21. Similarly, section 21 is screwed within section 22 and section 22 within section 23. Ring 33 is snapped into position within groove 39 before said section 21 is screwed into position within the bore of section 22. Plate 75 18 is then inserted upon head 29 of section 20

and said head 29 flattened to retain plate 18 thereon. These coupled members 18, 20, 21, 22 and 23 are inserted downwardly through bore 11 and the bore of tube 15 until flange 24 of section 23 engages the upper end of flange 6 whereby the coupled members are rotatably retained within flange 6. At this time, cap 30 is screwed onto section 23 by giving the cap 30 a righthand rotation. Upon edge 38 of cap 30 contacting the bowl 3, the section 23 is retained from 10 upward movement but is at the same time rotatably supported.

In the operation of the present pipe structure, tobacco is inserted within the tube 15 and supported by plate 18 therein. The tobacco is piled 15 sufficiently high for the uppermost portions thereof to be positioned within bore 11 of ring 10. By suction being applied to bore 34 of stem 9, air is drawn inwardly from bore 11 and upon a flame being applied to the tobacco therein, the 20 tobacco is ignited. Smoke from the burning tobacco is drawn through openings 16 to within tubular member 1. However, only as much smoke as can be drawn at a time through bore 25 34 can, at the same time, be drawn through openings 16, due to the similar cross sectional area of the two sets of passageways. Therefore, the smoker upon drawing, draws smoke from within tubular member 1, creating a partial vacuum 30 therein which in due time draws the smoke 35 through the openings 16, thereby assuring that the tobacco within bore 11 will continue to burn between draws and also the smoke within tubular member 1 will be given a chance to dissipate the heat therein by conduction through the light-weight metal of said member 1, thereby condensing the heavy oils, tars and moistures from the smoke, while at the same time, cooling the smoke.

The burning takes place within the bore 11 40 and, therefore, the heat is retained within this heat insulating chamber, permitting tubular member 1 to remain cool. As the tobacco is consumed, additional tobacco is positioned within bore 11 by giving cap 30 a righthand rotation 45 which will cause section 20 and sections 21, 22 and 23 to unscrew from one another, due to section 20 remaining non-rotatable, due to its connection to plate 18. Flanges 26 of said sections 20 and 22 and flange 40 of section 21 assure that 50 the sections unscrew in an even manner until said flanges 26 and 40 contact the lower edge of threads 35, whereby further upward movement of plate 18 is stopped. Some smokers of the present pipe will find it desirable to maintain the 55 burning portion of the tobacco at the top of ring 10, it being a matter of taste as to the amount of air which is to be delivered to the burning tobacco which determines the position of the embosses within or above bore 11.

To return plate 18, cap 30 is given a lefthand rotation whereby the sections 20, 21, 22 and 23 will progressively return to the position shown in Fig. 1 of the drawing. Flange 40 of section 21 will contact ring 33 of section 22 whenever 65 said section 22 should inadvertently become stuck and not rotate as desired and will thereby assure that section 22 will return to its closed position. Flanges 26 contact the inner face 37 of cap 30 and thereby maintain the sections at 70 their innermost position. It is obvious that additional members similar to members 21 or 22 may be included within the telescopic sections, if so desired.

Continued rotation of cap 30 unlocks the tele- 75

scopic sections from tubular member 1 and with the unscrewing of ring 12 permits the easy and rapid disassembly of the pipe structure whereby it may be conveniently cleansed by boiling in water or otherwise.

The present device is capable of considerable modification, but, however, any such changes as are made to the device shown and described herein which come within the scope of the appended 10 claims are deemed to be part of the present invention.

I claim:

1. An improvement in smoking pipe bowl assemblies comprising an angularly shaped tubular member, a tube mounted within said tubular member, means for progressively raising and lowering tobacco within said tube, said tube having openings formed through an end portion thereof, an annular flange formed extending from said 20 end portion of said tube, a ring of heat-insulating material having the bore thereof in line with the bore of said tube, a second ring detachably connecting said first ring to an open end of said tubular member and contacting said flange for 25 positioning the major upper portion of the outer side wall of said tube in spaced relationship to said tubular member and a stem member connected to the opposite end of said tubular member.

2. An improvement in smoking pipe bowl assemblies comprising a tubular member forming substantially a pipe bowl with stem extending therefrom, the base of said bowl portion having an opening formed therethrough, said tubular member having an inwardly extending flange formed around said opening, a tube having openings formed therethrough and having an end thereof mounted about said flange upon said bowl base portion, means for progressively raising and lowering tobacco within said tube detachably mounted within and closing said opening, and a tubular ring of heat-insulating material forming a tobacco firing chamber and being detachably connected to and closing the open end 45 of said bowl with the bore thereof in line with and adjacent to the bore of said tube.

3. An improvement in smoking pipe bowl assemblies comprising a tubular member forming substantially a pipe bowl with stem extending therefrom, the base of said bowl portion having an opening formed therethrough, said tubular member having an inwardly extending annular flange formed around said opening, the periphery of said flange being of a rectilinear configuration, a tube positioned within said bowl and having said flange inserted within a portion of the bore thereof, said tube having a plurality of openings formed therethrough, said tube bore having a cross sectional configuration of similar

shape and size as the periphery of said flange, a plate having a peripheral configuration similar to said tube bore configuration, slidably mounted longitudinally of and extending across said bore, interconnected members rotatably mounted within and closing said opening having said plate connected thereto, and a ring closing the open end of said bowl and having the bore thereof in line with the bore of said tube.

4. A smoking pipe bowl assembly comprising 10 a pipe bowl member with stem extending therefrom, a tube having a plurality of openings formed therethrough positioned within and having a portion of the outer side wall thereof spaced from said pipe bowl, a ring detachably connected 15 to and closing the open end of said pipe bowl, said ring having the bore thereof extending contiguous from the bore of said tube, a plate extending across and slidably mounted longitudinally of the bore of said tube, an opening formed 20 through the base of said bowl member, a plurality of threadedly interconnected telescopic sections rotatably mounted upon the base of said bowl and within said opening, one of said sections being connected to said plate, an end portion of each of said sections having a flange extending therefrom, and a cap capable of receiving 25 said section end portions therein being connected to one of said sections and retaining said section within said opening.

5. A smoking pipe bowl assembly comprising 30 a pipe bowl member with stem extending therefrom, a tube having a series of annular openings formed through the upper end portion thereof and being positioned within said pipe bowl, a 35 flange formed in the base of said pipe bowl retaining the lower end of said tube in spaced relationship relative to said pipe bowl, said tube having an annular flange formed at and extending from said upper end portion, a ring closing 40 the open end of said pipe bowl having the bore thereof extending contiguous from the bore of said tube, said ring having its lower face formed tapering downwardly and inwardly towards the center thereof, a second ring mounted on the periphery of said first ring and extending from 45 said lower face of said first ring, the extended portion of said second ring having its inner face tapered downwardly and outwardly, said tube flange being inserted within and in contact with 50 said inner face of said second ring, the inner face of said pipe bowl having threads formed on the upper portion thereof, said second ring having threads formed upon its periphery being in engagement with said bowl threads and means 55 for progressively raising and lowering tobacco within said tube.

HAROLD T. BLUM.
